PORTABLE CLOTHES HANGER HOLDER
AND CARRIERSamuel Kaplan, New York, and Louis Stark,
Brooklyn, N. Y., assignors to Kastar Incorporated,
Bronx, N. Y., a corporation of New York

Application July 11, 1950, Serial No. 173,126

4 Claims. (Cl. 224—42.45)

1

The present invention relates to a portable clothes hanger holder and carrier and more particularly to a portable clothes hanger, holder and carrier adapted to be secured to an automobile window by means of a supporting post and having a removable, unitary carrying handle and hanger supporting arm adapted to be hung on a conventional closet bar by means of a hook integral with such arm.

It is an object of the present invention to provide a portable clothes hanger holder and carrier that may be readily secured to an automobile window by having a supporting member that fits into the glass channels at the top and the bottom of the window and which may be secured thereto without the necessity of using any tools, or in any way altering or injuring the window frame or vehicle body itself as by placing any permanent holes therein or applying any fixtures thereto.

It is also an object of the present invention to provide a hanger supporting carrier that is detachably applied to the members used to secure the total structure to the window channels and which may therefore be removed from the car while still supporting the clothes carried on hangers and used as a carrying handle.

It is an object of the present invention to incorporate in the structure a carrying handle that will provide an easy and comfortable means for carrying the clothes thereon to and from the automobile, the carrying handle being especially designed to fit the human hand.

It is also an object of the present invention to provide a hanger supporting arm that may be readily hung onto the conventional clothes supporting bar found in closets, and when so hung will properly support the clothes and so position the hangers that they may easily be removed and then rehung again. Thus, when traveling, it would not be necessary for the passenger to remove the clothes from the hanger supporting carrier but they could all be easily carried from the car to the hotel room or wherever the party was staying temporarily, and hung in the closet there, still without having to remove the clothes from the hanger supporting carrier.

It is a further object of the present invention to provide a structure that is free from any chance of rattling. The supporting member is adapted to fit tightly against the window frame and the hanger support carrier is snugly wedged to the supporting member. Clothes hung on the hanger support carrier will have a tendency to tighten, not loosen this connection. This anti-rattling feature of the present invention is very important

in a device of the type herein disclosed. Even the smallest vibration noise or rattling can become extremely disturbing on a journey of any substantial distance.

5 A device embodying the present invention, although inexpensive to manufacture, is also of sturdy and durable construction which is also an important feature of a device of the type here involved, since it is likely to be subject to rough handling and abuse and probably will be loaded beyond what would be assumed to be normal capacity.

These and other objects and advantages of the present invention will be more readily apparent from the following description and drawing of one specific embodiment of the present invention in which drawing:

Fig. 1 is a partially broken away side elevation of a device embodying the present invention;

10 Fig. 2 is a partially broken away front elevation thereof;

Fig. 3 is a sectional view taken along line 3—3 on Fig. 1;

15 Fig. 4 is a sectional view taken along line 4—4 on Fig. 1, and;

Fig. 5 is a perspective view showing the hanger supporting carrier hung on a conventional closet rod and carrying a plurality of articles of apparel on clothes hangers.

20 The supporting post 10 is adapted to be held in position by the upper and lower window channels of an automobile window. Removably secured to the supporting post 10 is the hanger supporting carrier 11. The hanger supporting carrier 11 has a hanger hook receiving portion 12, a carrying handle portion 13 and a closet bar hook 14. The supporting post 10 comprises an upper member 15 and a lower member 16. The lower member 16 is threaded, and is slidably received in recess 17 of the upper member but is not threaded therein. The lower member 15 is provided with an end portion 18 having a depending flange 19, adapted to fit into the lower window channel. The upper end of the upper member 15 is similarly formed having an offset portion 20 and an upwardly projecting flange 21 adapted to fit into the upper window channel.

25 A ferrule 22 having a knurled exterior is threaded onto the lower member 16 and fits around the lower end of the upper member 15. The ferrule 23 is free to rotate relative to the upper member 15, and rotation of the ferrule 22, thus causes the lower member 16 to move relative to the upper member 15.

30 The hanger supporting carrier 11 is secured to

the supporting post 10 by means of pins 23 and 24. The pins 23 fit into vertical slot or groove 25 at the upper end of the upper member 15 and the pins 24 fit into the horizontal slot or groove 26. The supporting post 10 is formed in its upper portion in the shape of a rectangular channel 27 into which the securing portion 28 of the hanger supporting carrier 11 fits. Located in the securing portion 20 is a resilient wedging member 29 preferably made of rubber. The wedging member 29 when not inserted into the channel 27 is of slightly greater width than the channel thereby insuring a tight and secure fit when the hanger supporting carrier 11 is secured to the supporting post 10.

The hanger supporting carrier 11 is provided with openings 30 in the hook receiving portion 12. The hook portions of conventional clothes hangers can be inserted into these openings 30 and will be held therein no matter into what position the hanger supporting arm may later be placed. The carrying handle 13 is suitably shaped to provide a comfortable fit in the hand of a person. This is important since the clothes carried by the hanger supporting carrier 11 may amount to a considerable weight, and if the handle portion 13 were not suitably shaped, it would have a tendency to cut into the flesh of the person doing the carrying. The hook portion 14 is suitably shaped to fit around the conventional hanger bar in a closet and when the hanger supporting carrier is hung on the conventional closet bar, it will support the clothing hung thereon in the proper position for easy and quick removal or replacement.

In use the supporting post 10 is secured to the window of an automobile by first placing the flange 21 in the upper window channel then rotating the ferrule 22 until the flange 19 is tightly wedged into the lower window channel. The hanger supporting carrier 11 would then be separated from the supporting post 10 and used to carry the clothing to the car. To secure the hanger supporting carrier 11 to the supporting post the pins 23 would be placed in groove 25 by holding it in the dot-dash position shown in Fig. 1. Upon releasing of the hanger supporting carrier 11 the weight of the clothing hung from the hook receiving portion 12 will cause the hanger supporting arm to pivot around pins 23 into the position shown in solid in Fig. 1. In this position the pin 24 will fit into groove 26 and the resilient member 29 will be firmly wedged into channel 27. The hanger supporting carrier 11 will be held therein rigidly in position, and will not rattle due to the vibration of the car.

When the traveler reaches his destination the hanger supporting carrier 11 supporting the clothing, can again be separated from the supporting post 10 by rotating it into the position shown in dot-dash lines in Fig. 1 and then lifted a slight amount upwardly to clear the pins 23 of grooves 25. The clothing can then be carried by grasping handle 13 and hung in the proper position at the point of destination by use of the hook 14 (as is shown in Fig. 5). It can therefore be seen that a structure embodying the present in-

vention will provide a convenient means for transporting more bulky types of articles of apparel such as men's suits, coats, and women's dresses and coats.

5 We claim:

1. A portable clothes hanger comprising a supporting post, and a hanger supporting carrier releasably secured to said supporting post, said hanger supporting carrier having a hook receiving portion and a carrying handle portion said supporting post having a vertical slot and a horizontal slot, a pin on said hanger supporting carrier adapted to fit into said vertical slot and a pin on said hanger supporting carrier adapted to fit into said horizontal slot.

10 2. A portable clothes hanger comprising a supporting post, and a hanger supporting carrier releasably secured to said supporting post, said hanger supporting carrier having a hook receiving portion and a carrying handle portion said supporting post having a channel adapted to receive a portion of said hanger supporting carrier, and a resilient wedging member secured to said hanger supporting carrier and adapted to be wedged into said channel whereby said hanger supporting carrier is held against any vibrational movement relative to said supporting post.

15 3. A portable clothes hanger comprising a supporting post, a hanger supporting carrier, releasably secured to said supporting post, said supporting post having a vertical slot and a horizontal slot, a pin on said hanger supporting carrier adapted to fit into said vertical slot, and a pin on said hanger supporting carrier adapted to fit into said horizontal slot, a hollow channel in said supporting post, said hollow channel adapted to receive a portion of said hanger supporting carrier, a resilient member on said hanger supporting carrier adapted to be wedged into said channel.

20 4. A portable clothes hanger comprising a supporting post, a hanger supporting carrier, releasably secured to said supporting post, said supporting post having a vertical slot and a horizontal slot, a pin on said hanger supporting carrier adapted to fit into said vertical slot, and a pin on said hanger supporting carrier adapted to fit into said horizontal slot, a hollow channel in said supporting post, said hollow channel adapted to receive a portion of said hanger supporting carrier.
